UNITED STATES PATENT OFFICE.

HALL H. HOLDAWAY AND ARTHUR C. CANDLAND, OF SALT LAKE CITY, UTAH,
ASSIGNORS TO MARY E. HOLDAWAY, OF SALT LAKE CITY, UTAH.

ELECTRIC-WIRE CONNECTION.

1,098,501.

Specification of Letters Patent.

Patented June 2, 1914.

Application filed May 20, 1912. Serial No. 698,640.

To all whom it may concern:

Be it known that we, HALL H. HOLDAWAY and ARTHUR C. CANDLAND, citizens of the United States, and residing at Salt Lake City, in the county of Salt Lake and State of Utah, have invented certain new and useful Improvements in Electric-Wire Connections, of which the following is a specification.

10 Our invention relates to electric connections and has for its object to provide a device for connecting pliant wires, over which electrical energy is to be transmitted, to prevent said wires from twisting, breaking or 15 becoming entangled; and particularly refers to a connection in the electric wires between the receiver and the instrument of a telephone system, whereby the receiver may be used without the connecting wires becoming 20 twisted or tangled.

These objects we accomplish with the device illustrated in the accompanying drawings in which similar letters of reference indicate like parts throughout the several figures and as described in the specification forming a part of this application and specifically pointed out in the appended claims.

Figure 1 is an enlarged view in elevation of our device used as a splice or connection 30 in the wires. Fig. 2 is a longitudinal section through the same. Fig. 3 is a transverse section on line $\alpha\alpha$ of Fig. 1. Fig. 4 is a transverse section on line $\gamma\gamma$ of Fig. 1. Fig. 5 is an elevation of the device as used in a 35 telephone system.

In handling mechanical devices or apparatuses in which electrical energy is used, and where the wires over which said electric energy is transmitted are pliant, said wires 40 frequently become twisted and entangled to such an extent as to injure them and delay the operation of the device or apparatus. In the moving of desk telephones and in using the receiver of a great many other telephones, the wires conveying the electric current must be pliant and the handling of the instrument twists the connecting wires and causes them to double, and form short bends therein. This frequently breaks the wires. 45 Our purpose is to provide a swivel connection or joint in such wires, whereby the tendency to twist is obviated, and the instrument, of whatever nature, may be ro-

tated without any twisting of the connecting wires. To do this we have provided an electrical connection of a swivel nature consisting of a receiving tip A and an entering tip B. Said tip A consists of a cylindrically shaped metallic member 1 to which one of the electric current carrying wires 2 is connected, preferably by a soldered joint. A portion of the inner side of one end of said member 1 is cut out forming a shoulder 3. An insulating sleeve 4 is secured within said member 1 and within said insulating sleeve 4 is secured a metallic drum 5, within which drum a piston 6 is operated. A piston rod 7 is secured within the head of an adjacent drum 8, which in turn is secured in said tip B. To the head of said drum 5 is secured the other current carrying wire 2'. Between the piston 6 and the other head of said drum 5 and carried on said rod 7 is a spiral spring 9. An insulating guard 10 is fitted within the end of said member 1 and carried on the said wires. Said tip B consists of a metal cylinder 11, having a shoulder 12 cut there-around, thereby forming an extended lip 13 which is made to engage within said cylindrically shaped member 1. Within said cylinder 11 is provided the insulating sleeve 14 which carries therein a drum 8. One of said wires 2' is electrically connected with the head of said drum 8. The other head of said drum 8 is held in electrical contact with the drum 5, in the said tip A, by means of the spiral spring 9. Said cylinder 11 is connected with the other current carrying wire 2 preferably by soldered joint. The piston 6 with its rod 7 and spring 9 holds said drums 5 and 8 contiguous and in lateral contact forming an electric connection of wires 2' and at the same time members 1 and 11 are telescoped as far as the shoulders 12 and 3 and are held in electrical contact by the tension of said springs 9. The electric contact continues and the current passes as long as said lip 13 is telescoped within said member 1. The said spring 9 is made sufficiently strong to hold said members 1 and 11 so telescoped with the ordinary use or strain on said wires 2 and 2', thereby forming a swivel connection in said wires permitting either end to be rotated without injury or twisting of the other end.

While the device is small and the material

of the lightest commensurate with its uses, the weight will be such as to hold the wires straight and free from entanglement.

As will be obvious our device may be used in any place where electrical contact and connection must be maintained in pliant wires that are liable or have a tendency to twist or become entangled.

Having thus described our invention we desire to secure by Letters Patent and claim:

1. A swivel connection for pliant current carrying wires, consisting of a current carrying cylindrically shaped member; an insulating sleeve therein; a current carrying drum within said sleeve; a piston within said drum; and a current carrying cylindrically shaped member having a lip thereon adapted to telescope within said first mentioned cylindrically shaped member; an insulating sleeve therein; a current carrying drum within said last mentioned sleeve; a piston rod, one end of which is secured in the head of the last mentioned drum, and the other end in said piston; and a spring adapted to

hold said drums contiguous and said lip 25 portions of one of said current carrying members within the other.

2. A swivel connection for pliant current carrying wires, consisting of two hollow current carrying members partially telescoped; a drum in each of said current carrying members insulated from and rotatable therewith; a piston operative in one of said drums and contacting with the interior wall thereof to form an electric connection; a 30 rod having one end fastened to the head of the other of said drums and the other end secured in said piston; and a spiral spring carried on said rod to hold said drums normally contiguous.

In testimony whereof we have affixed our signatures in presence of two witnesses.

HALL H. HOLDAWAY.
ARTHUR C. CANDLAND.
